UNITED STATES PATENT OFFICE.

ARTHUR W. WALKER, OF MALDEN, MASSACHUSETTS.

COUNTERPOISE FOR STOVE DOORS.

Application filed April 23, 1925. Serial No. 25,316.

To all whom it may concern:

Be it known that I, ARTHUR W. WALKER, a citizen of the United States, residing at Malden, in the county of Middlesex and 5 State of Massachusetts, have invented certain new and useful Improvements in Counterpoise for Stove Doors, of which the following is a specification.

This invention relates to an improved 10 counterpoise for stove doors. More particularly it relates to an improved means for balancing the opened doors of ovens, broilers and the like, in gas and electric ranges for domestic use. Doors which open about a 15 hinge at a horizontal edge of the door tend to slam themselves open or shut as the center of gravity swings outward. To prevent this counterpoise springs are used, and it is an object of the present invention to provide improvement in such. 20

The recent trend of design has been to conceal the door springs within the frame of the stove, and in such construction the springs have usually been arranged vertically, in position to resist direct action of an arm which swings with the door, and this has involved the placing of the spring in a location where it is both subject to high heat and is annoyingly inaccessible for removal and replacement. Among the advantages of the 30 invention are that it provides a location and arrangement of spring where there is easy facility for the insertion, removal or adjustment of the spring; and that this is in a region not affected by proximity to the source of heat, only parts such as wire links or rods being subject to the heat of that region.

The invention is illustrated as it may be applied to a stove or range having two heat 40 chambers for cooking one above the other, with the gas flame or other source of heat, such as electric units, arranged between them, so that the upper chamber may constitute an oven while the lower chamber may 45 constitute a broiler. In such arrangement already known any arm moving with the door swings in a vertical plane, and it has been proposed to balance the doors, which are hinged at the bottom by providing a vertical 50 cal spring within the adjacent space that is closed by the door. As contrasted with this, the present invention provides a link or rod extending from the said arm on the journal of the door to some cool and easily 55 accessible place, as for example under the bottom of the stove, which stands on legs,

and there having connection with a bell crank which transmutes its action into horizontal direction and permits attachment to a spiral spring arranged for action horizontally in this cool part of the stove. There is the further feature of this construction that it permits of all of the springs for the doors, two in the instance illustrated, being arranged at the same point of anchorage 60 and being operated by simple wire links each running the necessary distance to its proper door. 65

In the accompanying drawings, one embodiment of the invention is illustrated; and 70 it is intended that the patent shall cover, by suitable expression in the appended claim, whatever features of patentable novelty exist in the invention disclosed. 75

In the drawings:

Figure 1 is an elevation, in section on line 1—1 of Figure 2, as it would appear looking outward toward the doors;

Figure 2 is a side elevation on line 2—2 of Figure 1 with both doors closed; 80

Figure 3 is a portion of a side elevation like Figure 2 showing the lower door open;

Figure 4 is a plan in section on line 4—4 of Figure 1; and

Figure 5 is a portion of an elevation like 85 Figure 1 showing a modification of the spring means.

Referring to the drawings, the doors 10 and 12 are openings for the oven and broiler compartments of a stove between which 90 compartments, the source of heat is suitably located as is common practice. The oven frame 14 is thickened at the lower corners of each door opening to provide horizontal bearings or journals 16 for the door. Seg- 95 mental arms 18 secured to or integral with the door, project inward and downward about the journals. A spur 20 on the peripheral edge of each arm engages a suitable stop 22 on the door frame when the door 100 has been swung to a horizontal position, and thus limits the opening swing. The lower compartment has a removable bottom 15 level with the bottom of the lower door. 100

In the embodiment of the invention illus- 105 trated one arm 18 of the upper door 10 is connected by a link 24, which in this instance is a simple wire with hooked ends, to a bell crank 26 mounted upon a bracket journal 28 attached to the frame 14 under the said broiler bottom 15. A similar but shorter wire line K³⁰ connects a link arm 18 of the lower 110

door to a second bell crank 32 mounted beside the first on the bracket journal 28. The bell cranks are severally connected to spiral springs 34, 36, which extend horizontally under the bottom, being anchored to bolts 38, 40, adjustably mounted on a second bracket 42 attached to the oven frame. This second bracket 42 has an angle plate with one web 42^a parallel to the spiral springs and provided with slots 44 through which extend the bolts 38 and 40 to which the springs are attached. The head of each bolt engages under the web, and its shank after rising through the slot is bent at right angles and so that the end of the bolt projects horizontally through an opening in the vertical web 42^b on the angle plate. Thumb nuts 46 threaded on these projecting ends of the bolts enable the bolts to be adjusted along the slots thereby altering the spring tension.

In operation the swing of a door causes its segmental arm 18 to turn about journal 16 and to pull upward on the wire link 24, thereby effecting a partial rotation of its bell crank 26, about its bracket journal 28. The pull of the link is transmitted by the bell crank 26 to apply tension to its spring, which in the present case is a horizontal elongation. This places restraint on the door's movement, to prevent it slamming open by its own weight. By suitable selection of the spring and adjustment of the anchor bolt 38 a spring tension may be predetermined so that the restraint of the door arm approximately counterbalances the tendency to swing caused by the weight of the door and the increasing moment of its center of gravity about its axis. By providing a slight tension on the spring when

the door is closed the door can be kept 40 tightly closed against its frame.

In the modification illustrated in Figure 5 the links 24 and 30 from the door arms are hooked directly through the ends of long bar springs 48 attached rigidly at their other 45 ends to an angle bracket 50 mounted on the oven casing. These bar springs, like the spiral springs of the preceding figures, are arranged in a space or region of the stove which is under the removable bottom of the 50 lower compartment, and so remote from the oven or broiler heat. This prevents any deterioration of the spring due to excessive heat, and also makes the springs very easily 55 visible and capable of manipulation for insertion, replacement or adjustment. The part of the mechanism which is in the less accessible and hotter regions is a simple wire hook.

I claim:

In a cooking range having a plurality of doors, one below the other, each on a horizontal hinge, the combination, with said doors, of an arm on each door swinging with the door; a stud on a stationary part 65 of the range, below the lower door forming a journal; a plurality of bell cranks mounted on said stud, one for each said arm; linkage connecting each bell crank with its arm; a bracket stationarily mounted at a 70 distance from the bell crank, below the lower door; and a plurality of spiral springs, all anchored to said bracket and each connected to one of said bell cranks and adapted to counterpoise one of the doors. 75

Signed at Boston, Massachusetts, this twenty-second day of April, 1925.

ARTHUR W. WALKER.
